UNITED STATES PATENT OFFICE

135,350

DESIGN FOR A BREAD SLICING BOARD

Carl E. Ulrich, Chicago, Ill.

Application February 1, 1943, Serial No. 109,403

Term of patent 3½ years

To all whom it may concern:

Be it known that I, Carl E. Ulrich, a citizen of the United States, residing at Chicago, in the county of Cook and State of Illinois, have invented a new, original, and ornamental Design for a Bread Slicing Board, of which the following is a specification, reference being had to the accompanying drawing, forming a part thereof.

In the drawing:

I claim:

The ornamental design for a bread slicing board, as shown.

CARL E. ULRICH.
